DESIGN FOR A TOY AIRPLANE

Edward H. Green, Chicago, Ill.

Application August 9, 1946, Serial No. 132,395

Term of patent 3½ years

(Cl. D34—15)

To all whom it may concern:

Be it known that I, Edward H. Green, a citizen of the United States, residing at Chicago, in the county of Cook and State of Illinois, have invented a new, original, and ornamental Design for a Toy Airplane, of which the following is a specification, reference being had to the accompanying drawing, forming a part thereof.

In the drawings:

Fig. 1 is a side elevation of a toy airplane embodying my new design, in an ascended position;

Fig. 2 is a side elevation in descending position;

Fig. 3 is a front elevation, in descending position;

Fig. 4 is an inverted plan, in descending position.

The essential features of my design reside in the portions shown in full lines on the drawing.

I claim:

The ornamental design for a toy airplane, substantially as shown and described.

EDWARD H. GREEN.
